UNITED STATES PATENT OFFICE.

HERMAN CHRISTIAN BINKELE, OF TIGARD, OREGON.

ELEVATOR CLOTHES DRIER.

Application filed January 2, 1926. Serial No. 78,891.

This invention relates to improvements in clothes drying apparatus.

The primary object of this invention is the provision of a compact clothes drying device adapted for household or other use, embodying novel means by which to elevate the same to an out of the way location for clothes drying purposes.

A further object of this invention is the provision of novel clothes drying apparatus embodying a compact assemblage of parts, with improved collapsible clothes supporting rods and novel means to elevate the same or lower the same.

15 A further object of this invention is the provision of an elevator clothes drier embodying means by which to slidably connect the same upon a wall, in order that the same may be elevated to any desired height for the purpose of supporting clothes for drying in an out of the way location, as just beneath the ceiling of a room in which the clothes are to dry.

Other objects and advantages of this invention will be apparent during the course of the following detailed description.

In the accompanying drawings, forming a part of this specification, and wherein similar reference characters designate corresponding parts throughout the several views,

30 Figure 1 is a side elevation of the improved clothes drier, showing its wall attachment and the same in elevated position supporting clothes for drying.

35 Figure 2 is a plan view of the improved clothes drier showing the clothes supporting arms thereon extended.

Figure 3 is a plan view of the improved clothes drier showing the clothes supporting arms collapsed.

40 Figure 4 is a fragmentary view, partly in section, showing the means for supporting the elevator part of the clothes drier in upwardly supported position.

45 Figure 5 is a fragmentary view, partly in section, showing the front details of the clothes drier support and elevator stem.

Figure 6 is a sectional view taken substantially on the line 6—6 of Figure 5.

50 Figure 7 is a fragmentary view, partly in section, of the upper portion of the elevator part of the clothes drier, showing the novel means for supporting the clothes supporting arms.

55 Figure 8 is a sectional view taken on the line 8—8 of Figure 7.

Figure 9 is a front elevation of the improved clothes drier, showing the clothes supporting arms thereof collapsed, except the two center arms, which are extended. 60

Figure 10 is a fragmentary sectional view showing a novel arrangement for supporting the clothes supporting arms.

Figure 11 is an enlarged sectional view taken substantially on the line 11—11 of Figure 4. 65

In the drawings, wherein for the purpose of illustration is shown only a preferred embodiment of this invention the letter A may generally designate the improved clothes drier, which may comprise a support B for attachment as upon a wall C of a building. Movable in the support B is an elevator member stem or rod E slidably mounted for elevation upon the support B by means F. At the upper end of the rod is a novel collapsible type of clothes supporting construction K.

The support B is preferably flat, and may be of wood or metal. It is preferably elongated, and attached against the vertical wall C as by means of detachable screws 15 or the like. 80

The slidable stem member or rod E is of any desired length, consistent with the height at which the support B is placed, and consistent with the height of the room in which the clothes are to be elevated. The rod E in cross section is preferably polygonal, and as is illustrated in the drawings, the opposite sides thereof are provided with vertical guide 85 grooves 19 and 20. In its forward surface or face the elevator stem E is deeply grooved at 21, to provide at opposite sides thereof the vertical parallel spaced tracks or beads 22 and 23, which serve their function in connection with the mounting and elevating means F to be subsequently described. 90

As to the means of mounting the vertical sliding stem E, it is preferred to provide a metal connecting piece 25, of channel shaped formation, which includes a rear wall 26 connected as by a screw element 27 to the supporting member B. This channel shaped member 25 includes the parallel side legs 28 outstanding from the front face of the support B, the free ends of which are provided with inturned facing projections or extensions 29 which slidably extend into the side grooves 19 and 20 of the elevator stem E, as is illustrated in Figures 5 and 6 of the drawings. This metallic guide member 25 is placed at the lower end of the support B, 100

105

110

and stabilizes the sliding movement of the member E with respect to the support B.

At the upper end of the support B, the means F includes a substantially channel shaped metal stem guiding and roller supporting member 30, the same being of U-shaped formation and including the connecting piece 31 attached by screws 32 to the support B, as illustrated in Figure 6 of the drawings. The member 30 provides the spaced parallel arms or legs 34 and 35, spaced a sufficient distance to permit the easy sliding of the member E therebetween. These arms 34 and 35 are longer than the arms 28 of the guide member 25, and extend forwardly beyond the plane of the front faces of the tracks 22 and 23, as is illustrated in Figure 6 of the drawings, and transversely in spaced relation across the face of the elevator stem E, said arms or legs 34 and 35 support a pin 37. On this pin 37, between the legs 34 and 35 is mounted a grooved wooden roller 39, which rotates within the groove 21 in the front face of the sliding stem E. On the opposite sides of the wooden roller 39 are placed rotatable rubber rollers 40 and 41, of a diameter to permit the riding upon the front edges of the tracks 22 and 23, and to limit the extent to which the wooden roller 39 enters the groove 21, and insuring an easy riding of the stem E as it is elevated or lowered thru the opening defined by the roller supporting and stem guide member 30.

Referring to the means of elevating the supporting stem E with respect to the support B, a cable 50 is connected at its lower end as at 51 to the slide rod or stem E at the lower end thereof; the cable 50 preferably being knotted and inserted through a suitable passageway transversely provided in the rod E, as is illustrated in Figure 4, to effect such connection 51. From this connection the cable 50 extends upwardly along the groove 21 of the slide stem or rod E, and is trained over the wooden pulley 39, preferably entering the groove 53 thereof. The free end of the cable 50 is trained downwardly, and hangs along the front of the rod E, and may be provided with a finger or hand engaging ring or element 55 at its free end.

As to operation, to elevate the member E and the clothes supporting means K at the upper end thereof, with respect to the support B, at its free end, since the pulley 39 operates on a fixed axis, merely by pulling and releasing the cable 50, the slide rod E and its clothes supporting means K may be elevated and lowered as desired.

In order to retain the slide rod E in a desired elevated relation, for supporting clothes at any desired height, it is preferred to provide a pawl pin 60, reciprocably mounted in a suitable cylindrical shaped box 61 placed in a passageway 62 thru the slide rod E. In the box 61 is a compression spring 63 suitably

connected at one end 64 to the pin 60, and at its opposite end resting against the front wall 65 of the housing 61, the force of the spring normally urging the inner end 66 of the pin 60 in projecting relation beyond the rear surface 68 of the slide rod or stem E, in position to ride along an inclined surface 70, and into a socket 71 provided in the support B, and the projection 66 enters the same to act as a detent for supporting the slide rod E against downward dropping. At the forward end of the pin 60 the same may support a thumb head 73, by means of which an operator may pull upon the pin 60 to withdraw the detent 66 from the socket 61, and therefore permit the lowering of the slide stem or rod E.

Since it will be desirable to locate the retaining pin 60 at various locations along the rod E, in order that the clothes supporting construction K may be elevated to a desired height it is preferred to provide a series of other passageways 75 thru the slide rod E, entirely similar to the passageway 62, for receiving the barrel 61 of the spring operated pin 60. A set screw 77 is adjustably provided in connection with the barrel 61, for lateral adjustment thru the slide stem E, as illustrated in Figure 11 of the drawings, into abutment with the barrel 61, to retain the same in any of the openings 62 or 75 in which the same may be placed. It is to be particularly noted that the outer end of this set screw 77 enters one of the side grooves 20 of the slide stem E, and thus serves as an abutment which the arm 28 of the member 25 engages to limit the upward elevated extension of the slide rod or stem E with respect to the support B.

Referring to the clothes supporting construction K as carried at the upper end of the elevator rod or stem E, as is illustrated in Figures 2 and 10 of the drawings, a metal bracket 80 is carried at the very top of the stem E, secured in countersunk relation at the rear side of the stem E, between its ends, as by a screw or analogous securing element 81, this member 80 from its intermediate secured portion having laterally extending supporting arms 82 and 83 which project in a diverging relation at opposite sides of the stem E. At their free ends the arms 82 and 83 support an arcuate shaped piece of wire 85, which may comprise a part of the collapsible supporting arm bracket construction, the same being bowed transversely between the arms 82 and 83 across the face of the stem E in spaced relation therewith, one end of the supporting segment 85 having a head 88 thereon secured in fixed manner with the arm 83 of the bracket 80. The opposite end of the arcuate segment 85 is screw threaded and adapted for extension thru a suitable opening in the arm portion 82 of the bracket 80, to receive a nut 89, as illustrated in the drawings, in order to stably mount the segmental supporting bracket portion 85 in the relation described.

Clothes supporting arms or bars 90 are provided at their pivoted ends with transverse openings thru which the segmental supporting member or wire 85 is received, so that said supporting arms 90 are pivoted upon the bracket segment 85 in independent manner. Between the adjacent pivoted arms 90, wooden spacing washers 92 are rotatable on the segmental shaped member 85. The washers 92 so space that when in place the arms 90 have a limited lateral movement, and are free to pivot on the arcuate member 85 so that when collapsed the arms will lie parallel with each other in vertical depending relation, parallel with the elevator stem E, and when extended they may be readily disposed with respect to each other about the segmental supporting member 85, radiating therefrom with respect to the center from which the segment 85 is struck.

Novel means is provided to collapsibly support the arms 90, comprising a supporting bracket 95, substantially similar to the bracket 80 above described, the same being attached to the slidable elevator stem E below the bracket 80, in a determined spaced relation, and the same intermediate its ends being countersunk inwardly of the rear surface of the stem E and secured thereto in appropriate manner. This bracket 95 includes laterally extending arms 97, at each side of the sliding rod E, similar to the arms of the bracket 80, and at the outer ends said arms 97 support an arcuate wire supporting bracket portion 98, similar in formation and attachment to the bracket 85 above described.

For each arm 90 of the clothes supporting construction K a collapsible brace arm 99 is provided, each of the same being looped at its lower end and pivoted on the segmental bracket portion 98, and at its opposite end being looped at 100, and pivotally supporting a substantially rectangular shaped clothes link 101, provided with an opening 102 therein in which its respective clothes supporting arm 90 is slidable.

It is preferred to brace the segmental supporting portions 85 and 98 in a predetermined spaced relation against movement, and to this end a wire bracket 105 is provided, secured at its intermediate portion 106 by means of securing elements 107 upon the stem E, in the groove 21 thereof. The upper end 108 of this bracket 105 is diagonally inclined outwardly from the slide rod E, and secured as by looping at 109 to the intermediate portion of the segmental shaped member 85. Similarly the lower portion of the brace 105 is diagonally inclined downwardly, at 110 away from the slide stem or rod E, and looped at 111 about the arcuate supporting bracket portion 98, between the ends thereof.

As above mentioned each supporting arm 90 is slidable in the opening 102 of its detent link 101. Inwardly of the top edge 115 of each of

the supporting arms 90 is provided a recess 116, defining an abrupt shoulder 117 facing towards the pivoted end of the arm.

As above mentioned the collapsed relation of the arms 90 are parallel in depending relation along the slide rode E. When it is desired to extend the clothes supporting arm 90 in right angled relation with respect to the slide stem E, for supporting clothes, it is merely necessary for the operator to lift the supporting arms 90 upon its pivot, and this action will likewise cause a lifting of the brace arm 99, incident to the detent link connection 101. Upon this upward movement of the arm 90 the link 101 will slide rearwardly towards the pivoted end of the arm, as is obvious, due to the eccentric pivoting of the supporting arm 90 and its brace arm 99. This will continue until the arm 90 is elevated above a horizontal position, and at which time the link 85 101 thereof will have slipped past the recess 116. Upon dropping of the arm 90 the link 101 will then slide forward and drop into the recess 116, against the shoulder 117, and the brace arm 99 will then be diagonally positioned for horizontally supporting the clothes supporting arm 90 in a right angled relation with respect to its slide rod E.

From the foregoing description of this invention the operation of the improved clothes supporting device will be obvious. The clothes drier may be elevated to the ceiling of the room in which the same is positioned, and the same may be raised and lowered without stooping or bending beneath drying clothes, by merely pulling upon the cable of the construction above mentioned. The novel roller construction for the slide rod E insures against defacement of the elevator stem, and facilitates the operation of the device. The metal retaining parts for the slidable stem are shaped and formed in a compact relation, and do not provide cumbersome projections upon which parts of clothes are apt to catch. The collapsible brace means for supporting the arms are cooperably mounted in novel relation with respect to the clothes arms to insure the automatic catching of the clothes supporting arms when the same are lifted above the horizontal, as above described. To release the arm 90 for collapsing it is merely necessary to lift the link of the arm out of its recess and move the same forwardly towards the free end of the arm and then drop the arm 90, and the latter will swing to its collapsed vertical position.

Various changes in the shape, size, and arrangement of parts may be made to the form of invention herein shown and described, without departing from the spirit of this invention or the scope of the claims.

I claim:

1. In a clothes drier of the class described the combination of a support, a slide stem having a pair of spaced tracks at the front 130

surface thereof with a groove therebetween, bracket means carried by the support engaging said slide stem to slidably connect the stem for movement in a vertical path upon 5 said support, said bracket means including yieldable rollers rotatably carried thereby upon which said tracks ride, clothes supporting means carried by the slide stem, means to elevate the slide stem with respect to said 10 support including a pulley rotatably carried by the bracket means between said yieldable rollers and operating within said groove, and a cable trained over the pulley and connected at one end to the lower end of said slide stem 15 below the bracket means and at its opposite end being adapted to be engaged by an operator.

2. In a clothes drier the combination of a vertical support, a lower U-shaped bracket 20 mounted on the support including arms projecting outwardly therefrom and inturned extensions, an upper bracket carried by the support having an opening therethrough vertically aligning with the projections of the 25 lower bracket, said upper bracket at the outer end thereof having spaced rollers projecting into the opening thereof, a vertical slide stem slidably mounted in the opening of the upper bracket, said slide stem inwardly at opposite 30 sides thereof having grooves into which the projections of the lower bracket extend for guiding the vertical sliding movement of the slide stem with respect to said support, said slide stem at the front thereof having spaced 35 tracks with a groove therebetween, the tracks engaging the spaced rollers of said upper bracket of the support, a pulley rotatably carried by said upper bracket between said above mentioned spaced rollers and rotatably extending 40 into the groove between said tracks at the front of the slide stem, a cable trained over said pulley and extending downwardly along the groove between said tracks and at its lower end being secured adjacent the lower 45 end of said slide stem, means to hold the slide stem in desired elevated relation with respect

to said support, and clothes supporting means at the upper end of said support.

3. In a clothes drier the combination of a 50 movable supporting member, a bracket connected upon the movable supporting member having laterally extending forwardly divergent bracket arms extending beyond the sides of the supporting member, an arcuated segmental shaped supporting wire connected at its ends on said bracket arms at the ends of the latter and extending transversely across the front of the supporting member in spaced relation therewith, clothes hanging arms 55 pivotally mounted on said supporting wire, and means to collapsibly support said last mentioned arms.

4. In a clothes drier of the class described, a supporting member, a pivoted arm on the member, a brace pivoted on the member below the pivot arm, a pivoted detent loop link 60 on the free end of said pivoted brace, said pivoted link having a loop opening therethrough of greater depth than the dimension of said pivoted arm, said pivoted arm having a recess inwardly of the top edge thereof and the pivoted arm being slidably extended through the opening of said detent link so that when the arm is horizontally elevated the detent link at its free end will engage the 65 said recess, with the pivot end of the link farther towards the free end of the arm to support the arm horizontally for clothes supporting purposes.

5. In a clothes drier, the combination of a 70 support, a bracket on the support having a vertical opening therethrough, a clothes supporting rod slidable in said vertical opening, a pulley rotatably supported by the bracket 75 at the front face of said rod on the opposite side of the rod with respect to the support, and a cable trained over said pulley having one end thereof free with the opposite end thereof connected to the clothes supporting rod below said pulley.

HERMAN CHRISTIAN BINKELE.
